BOWLING PIN CLEARING DEVICE

Howard E. Hutzelman, Wilmington, Del.

Application May 7, 1947, Serial No. 746,429

11 Claims. (Cl. 273—54)

1

This invention relates to mechanism for the removal of bowling pins from the bowling alley and/or gutters. More particularly, this invention relates to mechanism for the removal of fallen pins from the bowling alley and/or gutters without altering the positions of any pins which remain standing.

Bowling has become increasingly popular as a recreational activity, and the number of alleys and establishments for bowling has increased accordingly. Originally, all the work of setting pins, removing fallen pins, and returning the ball to the bowler was performed manually by "pin-boys." In order to increase efficiency and to speed up the game, mechanical devices were produced which aided the "pin-boy" by accurately placing the pins in proper position. Recently, the trend has been to utilize mechanical devices to replace the "pin-boy" entirely, and in line with that trend, devices have been produced which automatically clear the bowling alleys, set pins, and return the ball to the bowler. However, the prior devices have not been completely successful in eliminating the "pin-boy" because it frequently occurs that several pins remain standing, either in their original position, or in a slightly altered position, while fallen pins still remain on the alley-bed or in the gutters. When this occurs after only the first ball has been thrown, the fallen pins must be removed without altering the position of the standing pins before the second ball may be thrown. There have been several proposed devices known to the art, such as the use of a tiltable alley-bed, the use of flexible sweeps, and mechanisms designed to locate and pick up the standing pins while the alley is cleared, the pins then being replaced on the alley. None of the above-mentioned devices have been widely adopted, because they either failed to remove the fallen pins in a satisfactory manner while leaving the remaining pins standing in the positions taken after the first ball had been thrown, or the mechanisms for satisfactorily performing the above function were too complicated for a practical commercial unit.

The object of this invention is a mechanism capable of removing fallen pins from the alley-bed and the gutters without disturbing the standing pins. Another object is such a mechanism which is simple in construction, reliable, and easy to maintain. A further object is such a mechanism capable of automatic action in combination with conventional pin-setting and ball return devices. Further objects will become ap-

2

parent as the invention is described in detail hereinafter.

The above objects are achieved by the use of a novel "plow" and "hold-down" mechanism. This mechanism is capable of use with well-known types of pin-setting devices, and with well-known ball return devices, but such devices do not constitute any part of this invention.

One embodiment of the invention is shown in the drawings accompanying this description. In the drawings:

Figure 1 is a plan view of the pin clearing device taken on line 1—1 of Figure 2;

Figure 2 is a side elevation taken on line 2—2 of Figure 1;

Figure 3 is a sectional view through a portion of the hydraulic cylinder and piston, the piston rod connection to the plow, and the disabling control bar;

Figure 4 is a sectional view through the piston; Figure 5 is a perspective view of the mechanism, some parts being deleted, and other parts fragmented for greater drawing clearness;

Figure 6 is a side elevation of a typical alley plow showing a mechanical individual control drive and disabling arrangement, taken on line 6—6 of Figure 7;

Figure 7 is a sectional view of five adjacent alley plows taken on line 7—7 of Figure 6.

Referring in greater detail to the drawings, the carrier frame is formed by two similar structural elements 10 separated by spacers 22 and held in rigid assembly by spacer bolts 45. To the upper element are fastened the four shaft support bearings 25, the rear two supporting shaft 27, and the forward two supporting shaft 50. Four support links 26 are connected pivotally to the fixed bearings 43 and the two shafts, two links going to each shaft. Plow roller tracks 23 are secured in proper position between the structural elements 10 and guide the six alley plows 11 and the two gutter sweeps 12 by means of the eight V-rollers 21 fastened to each of the plows and sweeps by means of studs 24. Fastened rigidly to the upper structural element 10 above the alley plows 11 are six hydraulic cylinders 13, and similarly fastened above the gutter sweeps are two hydraulic cylinders 14. Each of the alley plows is equipped with an ejector brush 20 on either side, this brush being made of stiff bristles or other suitable resilient material. The alley plows are connected by a collar 44 to tubular piston rods 15 while the gutter sweeps are connected to solid piston rods 16. Extending beyond the forward edge of the alley plows are the con-

50
45
55

trol rods 19 with a cross bar 18 and a compression spring 17. The rods are inserted in the tubular piston rods 15 so that when the spring 17 is fully extended, the rod 19 does not touch steel ball 48 in piston 46. Leakage between rod 19 and tubular rod 15 is prevented by retainer rings 49 and packing 51. The piston 46 also contains packing 47.

The two carrier arms 29 are pivotally mounted on shaft 27 and are rigidly fastened to base plate 30. A hold-down pad 31 (sponge rubber or other resilient material) is fastened to the underside of plate 30. On the top of plate 30 is mounted the shaft block 40 which carries the trunnion shaft 38. A flanged roller 39 is mounted at each end of shaft 38. Guide tracks 32 are rigidly mounted on the two kick-backs K. The two locking yokes 33 are pivotally mounted on studs 42 and rigidly connected together by a shaft 41. It should be noted that studs 42 are supported by brackets 52 on kick-backs K, and that the two locking yokes 33 constitute the "operating yoke" mentioned below. A hydraulic cylinder 35 is pivotally fastened to support 36 by means of a stud 37 and is connected to the shaft 41 by the piston rod 34. The entire assembly is counterbalanced by means of weighted counterbalance cables 28.

The hydraulic fluid lines and source of power are not shown in order to preserve clarity of illustration, as they are conventional and well-known.

The letter symbols all refer to conventional bowling alley equipment, and have a meaning as follows: A—alley-bed; G—gutter; P—bowling pin; M—automatic pin-setting mechanism; L—alley light; C—alley curtain; and K—gutter kick-back.

The operation of the mechanism is as follows:

The entire pin clearing device is held in the retracted position indicated by the dashed lines in Figure 2 whenever it is not engaged in clearing the alley. Upon actuation, either by means of a bowler-controlled switch or a switch controlled automatically, for instance, by the weight of the ball in the pit, the entire assembly swings downward and forward. Carrier arms 29 are supported by shaft 50 until the flanged rollers 39 enter upon the guide tracks 32, at which time the downward motion of the pin locking device is halted. As the pin clearing device continues descending, carrier arms 29 pivot on shaft 27, and the pin locking device moves forward until the flanged rollers enter the operating yoke, the yoke then being held open and the piston rod 34 fully retracted. The halting of the pin locking device also halts the forward motion of the clearing device. At this point, the pin holding device is directly above the pins, but does not touch them. Pressure is then applied to the top of cylinder 35, causing the operating yoke to move the pin locking mechanism downward, thereby engaging the tops of the standing pins, firmly clamping them in position. Since the flanged rollers are now locked in an immovable position, being held by the operating yoke 33, the pin locking mechanism is held stationary, and carrier arms 29 prevent any motion of the carrier frame.

Pressure is now applied to the eight hydraulic cylinders 13 and 14 individually, in any predetermined order, so as to cause the pin clearing plows and the gutter sweeps to move forward in such selected order, removing fallen pins from the alley-bed and gutters to the pit. The pin clearing plows are positioned to pass by any standing pin in its normal position. One pre-

ferrered sequence of advancement of the plows and sweeps is shown in Figure 5. The positive force of the plows in combination with the ejector brushes will effectively clear the fallen pins from the alley, even though some standing pins directly prevent movement of some of the plows towards the pit.

When all the plows and sweeps have reached the end of their stroke, the pressure on the cylinders 13 and 14 is reversed, and the plows and sweeps return to the original position in the carrier frame. The pressure is reversed in hydraulic cylinder 35, lifting the operating yoke 33 and thereby lifting the pad off the pins. The entire assembly is then retracted to the out-of-the-way position.

In the event one of the standing pins was moved out of its usual position into the path of a plow, that individual plow would be disabled from further movement. The sequence would be as follows: The cross bar 18 carried by the control rod 19 would engage the upper portion of the interfering pin before the plow surface would contact the lower portion of the pin. With continued forward motion of the tubular piston rod 15, the now stationary control rod 19 would force the steel ball 48 away from its seat in piston 46, thereby breaking the seal and allowing the hydraulic fluid to pass through the piston. The forward motion of the piston would cease, and the plow would be stationary. With reversal of the pressure, the ball would seat on the opposite end of the piston, and upon reTRACTING motion, spring 17 would restore control rod 19 to its usual position.

To remove all the pins before resetting the alley, the operation would be the same, except that the operating yoke would not be lowered sufficiently to cause the pin locking mechanism to engage the standing pins. This could be regulated by regulating the length of the stroke of piston rod 34 or by providing engaging stops for the operating yoke.

The mechanism in the retracted position affords a clear view of the pins to the bowler, and is completely out-of-the-way of the pin-setting mechanism. As is shown in Figure 2, it does not interfere with the conventional elements of the alley.

The means of actuating and controlling the mechanism depends entirely upon the preference of the establishment. If it is desired to make the operation automatic and independent of the wishes of the bowler, switching means actuated by the weight of the bowling ball in the pit may be used. Otherwise, a simple push-button operation panel can be provided at the scoring stand or similar location. The latter method would have the advantage of eliminating movement of the device when such movement is unnecessary, such as when no fallen pins remain on the alley after the first ball has been thrown, or when all of the pins have been knocked into the pit.

It will be obvious that many alterations may be made without departing from the basic invention herein described.

Figures 6 and 7 show a mechanical means for obtaining exactly the same drive, control, and disabling of the alley plows and gutter sweeps as has been described for the hydraulic cylinder arrangement.

Referring to Figures 6 and 7, the alley plows 60, V-rollers 61, roller tracks 75, and spacers 76, are almost identical with those parts described earlier, numbered 11, 21, 23, and 22, respectively.

ly. The upper part of each of the alley plows 60 is arranged to accommodate the mechanical control bar 62 and control rod 63 in three slide bearings. Drive latch 69 is connected pivotally to the alley plow 60 on stud 78. Return lug 71 is a part of plow 60. Support brackets 77 are mounted on the roller track frame composed of roller tracks 75 and spacers 76, and support shafts for sprockets 53, 54, 55, 56, 57, and 58, upon which the continuous roller chains 72 operate. The complete plow unit, only a part of which is shown, contains six alley plows and two gutter sweepers, as described in the first part. The drive chains 72 for each plow or sweeper, are exactly the same length, but the heights of the centers of sprockets 57 and 58 for each chain are varied in order to obtain the required spacing arrangement for the plows as illustrated in Figure 5. The entire eight chains are driven simultaneously through drive shaft 74, from main drive chain 73 and sprocket 59. The motor and sprocket to drive chain 73 would be mounted on a stationary support directly above shaft 74, at a height corresponding to the position of fixed bearings 43 on Figure 2, and are not shown on the drawings. Restoring studs 66 are attached to track spacers 76 at the position relative to drive latch 69 when the plows are fully retracted, as shown in Figure 6. Drive studs 70 are attached to each of the eight chains 72. A locking stud 67, stop collar 68, and return collar 65 are attached to each control rod 63.

The operation of this mechanism is as follows: After the framework has been lowered and the standing pins clamped to the alley-bed by the mechanisms previously described, a suitable switch would be actuated to start the motor and sprocket for chain 73, initiating the alley plow and gutter sweeper cycle. The chains 72 are driven in the direction such that the under portion of the chain moves forwardly, and the drive studs 70 are so located that the drive latch 69 for the center plow will first be engaged. Rotation of the drive latch 69 is prevented by the locking stud 67 in control rod 63, so the plow 60 is driven forward. At a fixed interval after the start of movement of the center plow, studs 70 in drive chains 72 for the respective plows adjacent to the center one engage their respective drive latches 69 and start movement of the next two plows. In a like manner, all of the plows and gutter sweepers are driven forward. However, when the forward position for any plow is reached, stud 70 passes upward around sprocket 56, disengaging from the plow. The varying heights of sprockets 58 are such that all drive studs 70 will reach a position at the bottom of sprockets 55 at exactly the same time. In this position, they will engage return lugs 71 and return all plows at the same time, to a point where the drive studs 70 disengage from return lugs 71 at sprockets 54. This position of the drive studs 70 is the end of a cycle of a fixed number of motor revolutions determined by a suitable automatic cut-off switch. It can be seen that, since all chains 72 are the same length, when the next cycle starts, there will be intervals between the times the respective drive studs 70 pass through the different distances between their respective points of disengagement from lugs 71 and their respective points of engagement with drive latches 69.

When a standing pin interferes with the motion of an alley plow 60, the upper portion of that standing pin will arrest the motion of con-

trol bar 62 thereby moving locking stud 67 out of drive latch 69, allowing the latch to pivot about stud 78, thereby disengaging the plow from the driving stud 70, and stopping its movement. The return lug 71 will be picked up by stud 70 on its return stroke, and as the plow is brought to its rear position, the released latch 69 is engaged by the restoring stud 66, which pivots the drive latch back to its latched position.

10 The same chain drive method is used for the two gutter sweepers (not shown), but these sweepers carry no control bar, so a lug similar to 71 would replace the drive latch arrangement for these sweepers.

15 I intend to be limited only by the following claims:

I claim:

1. In a pin clearing mechanism for the removal of unwanted pins from a bowling alley, the combination of a hold-down pad, a retractable carrier having a series of guide tracks, rigid alley clearing plows and gutter clearing sweeps guided by said tracks, and means of advancing and retracting each of said plows and sweeps at predetermined intervals and means for activating said plows concurrently with the disposition of said hold-down pad in a position to fix standing pins, whereby said plows may be moved forward to remove fallen pins while the standing pins are held upright by said hold-down pad, said plows being moved simultaneously and said carrier being retractable for the purpose of removal to an out-of-the-way position to permit operation of the alley in bowling.

2. In a pin clearing mechanism for the removal of unwanted pins from a bowling alley, the combination of a hold-down pad, a retractable carrier having a series of parallel guide tracks, rigid alley clearing plows and gutter clearing sweeps positioned on said guide tracks, means of advancing and retracting each of said plows and sweeps as a group over the portions of the alley between the forward pin and the pit at predetermined intervals, and means of automatically disabling any plow whose path is occupied by a standing pin and means for activating said plows concurrently with the disposition of said hold-down pad in a position to fix standing pins, whereby said plows may be moved forward to remove fallen pins while the standing pins are held upright by said hold-down pad.

3. In a pin clearing mechanism for the removal of unwanted pins from a bowling alley, the combination of a hold-down pad, guide tracks and operating yokes to position and lock said hold-down pad, a cooperating retractable carrier containing a series of parallel guide tracks, alley clearing plows and gutter clearing sweeps positioned on said guide tracks, means of advancing and retracting each of said plows and sweeps at predetermined intervals, and means of disabling any plow whose path is occupied by a standing, hold-down pad engaged pin, from further advancing motion and means for activating said plows concurrently with the disposition of said hold-down pad in a position to fix standing pins, whereby said plows may be moved forward to remove fallen pins while the standing pins are held upright by said hold-down pad.

4. The mechanism as claimed in claim 3, wherein the means of advancing and retracting the plows and sweeps comprises hydraulic cylinders, pistons, and piston rods connected to the said plows and sweeps.

75 5. The mechanism as claimed in claim 3,

wherein the plows carry brushes of resilient material.

6. The mechanism as claimed in claim 3, wherein the means of disabling a plow whose path is occupied by a standing pin comprises an extending rod in a tubular piston rod, said rod being adapted to unseat a ball-valve in the piston when depressed relative to the piston rod.

7. In a pin clearing mechanism for the removal of unwanted pins from a bowling alley, the combination of a hold-down pad, a retractable carrier, rigid alley clearing plows and means for advancing and retracting each of said plows at predetermined intervals including an individual drive chain for each plow.

8. The mechanism of claim 7, wherein each plow is provided with disabling means.

9. The mechanism of claim 8, wherein the disabling means includes a control bar, a locking stud, a drive latch, and a driving stud, whereby arresting of the control bar will move said locking stud out of said drive latch to disengage the plow from said driving stud.

10. In a pin clearing mechanism for the removal of unwanted pins from a bowling alley, the combination of a hold-down pad for fixing standing pins, a plurality of rigid plows for removing fallen pins, disabling means mounted on each plow for disabling said plow upon contact with a standing pin and means for activating said plows concurrently with the disposition of said hold-down pad in a position to fix standing pins, whereby said plows may be moved forward to remove fallen pins while the standing pins are held upright by said hold-down pad, said dis-

abling means including a tubular piston rod and a piston, an extending rod in said piston rod, said extending rod being adapted to unseat a ball valve in said piston when depressed relative to the piston rod, said rods cooperating with said plurality of plows to disable any one of said plows upon contact with a standing pin.

11. In a pin clearing mechanism for the removal of unwanted pins from a bowling alley, the combination of means for fixing standing pins, a plurality of rigid means for removing fallen pins, an individual disabling means for halting each of said rigid means upon contact with a fixed standing pin, means for activating said removing means with the disposition of said fixing means in a position to fix standing pins, whereby said removing means may be moved forward to remove fallen pins while the standing pins are held upright by said fixing means, and means for advancing said plurality of rigid removing means on an uneven horizontal front whereby fixing of fallen pins against standing pins is avoided by contacting fallen pins on the alley by one or more of said removing means on said uneven horizontal front.
